UNITED STATES PATENT OFFICE.

RICHARD NASON FRIEND, OF SIOUX CITY, IOWA.

FLASH-LIGHT SUPPORT.

1,367,369.

Specification of Letters Patent.

Patented Feb. 1, 1921.

Application filed March 6, 1918. Serial No. 220,834.

To all whom it may concern:

Be it known that I, RICHARD NASON FRIEND, a citizen of the United States, and a resident of Sioux City, in the county of Woodbury and State of Iowa, have invented certain new and useful Improvements in Flash-Light Supports, of which the following is a specification.

The present invention relates to flash-lights.

The structure presented in my United States Patent No. 1,237,191 issued August 14, 1917 suffers from defects chiefly as follows: The support is not readily applied to the flash-light and must be permanently fixed thereto. The base is small to normally cover the end of the flash-light thereby giving the structure a top-heavy tendency when in use, especially if the flash-light has a large head; furthermore, the device has proven to be unstable.

The objects, therefore, of the present invention are manifold,—first, the provision of a support adapted to be instantly applied to and detached from a flash light; second, the production of a support for a flash-light having an adjustable base which negatives any top-heavy tendency; third, the production of a support which may be instantly pivotally attached to a flash-light and adapted to be swung into a position adjacent the sides of the flash light when not in use; and fourth, the production of an improved flash-light support inexpensive in manufacture yet stable and thoroughly dependable in use.

With these and other objects in view the invention consisting in the construction, combination and novel arrangement of parts, will be fully understood from the following description, reference being had to the accompanying drawings, which form a part of this application and in which like characters of reference indicate corresponding parts throughout the several views, of which:

Figure 1 is an elevation of a flash-light equipped with the preferred embodiment of the invention;

Fig. 2 is a plan of the same;

Fig. 3 is a rear elevation of the same;

Fig. 4 is an enlarged perspective view of the support detached from the flash-light;

Fig. 5 is a longitudinal section of one of the base cross members; and

Fig. 6 is an inverted plan of the same. 55

While I have illustrated and hereinafter described an embodiment suitable for practising the invention, I would not be understood as being limited to the specific structure chosen for illustration, for various alterations and modifications in the details of construction and arrangement of parts may be made without departing from the spirit and scope of the invention as defined in the appended claims. 60 65

Referring, now, to the illustrations, 7, is a flash-light having an elongated barrel, 8. The support includes a resilient segmental band 9, adapted to be sprung onto the barrel of the flash-light, as clearly shown. As the 70 said band extends more than one-half the distance around the barrel, it is evident it cannot be displaced from the barrel except at the will of the user. On diametrically opposite sides of the band are pivoted the 75 ends of two U-shaped supports, each including two parallel arms 10, and a web which interconnects the lower ends of the arms. In order to render the webs extensible and retractable, the said U-shaped members are 80 preferably formed of separate strips 10, the lower end portions, 11 of which are bent laterally toward each other, an off set 12, being provided in one of said portions to permit the portions to overlap each other. 85 One of said portions is provided with aligned studs 13, having beveled heads 14, slidably engaged within an externally beveled slot 15, in the adjacent portion 11. The arms, 10, of the support are positioned one outside the 90 other, and are pivoted to the band as at 16. The end portions of the arms adjacent the band are flat as at 17, and their intermediate portions are slightly curved transversely to conform somewhat to the contour of the barrel of the flash-light. The lower end portions 18, of each U-shaped support are extended at an angle to the upper portions and in the opposite direction to the corresponding portions of the companion support, the said 95 angle being provided to adapt the webs of the supports to be placed edge to edge adjacent the rear end of the flash-light when the intermediate portions of the supports are

10

brought into parallelism one outside the other as shown in Fig. 2 and in dotted lines in Fig. 1; and in assuming this position the concavo-convex portions of the innermost arms 5 10, impinge the barrel of the flash-light and are impinged by the corresponding portions of the companion support, thereby preventing relative displacement between the supporting members as well as between the barrel 10 and the said members.

The band 9 is applied to substantially the center of gravity of the barrel, and on the opposite side of the barrel from the sliding switch 19, to permit free operation of the latter.

In operation, the U-shaped supports are placed at an angle to each other, as clearly shown in Fig. 1. To prevent any tendency of the support to tip laterally the bases or 20 webs of the U-shaped supports may be suitably extended as presented in Fig. 3. The adjustable webs however are arbitrary, and if desired may be fixed, or the arms and web of each member may be an integral part.

Having thus described my invention, what I claim as new and desire to secure by Letters Patent is,—

1. A support for a flash-light having a barrel, including a yieldable band adapted 30 to be sprung onto the barrel, and a pair of U-shaped supports having their ends pivoted one inside the other on opposite sides of the band.

2. A support for a flash-light having a barrel, including a band adapted to be placed 35 on the barrel, and a pair of U-shaped supports having their ends pivoted one inside the other on opposite sides of the band, the supports being adapted to be so turned that 40 their arms will be in parallelism with the barrel and their cross members will extend across the end of the barrel.

3. A support for a flash-light having a barrel, including a band adapted to be placed 45 on the barrel, and a pair of substantially U-shaped supporting members, each comprising elongated arms, and webs interconnecting the lower ends thereof, the upper ends 50 of the arms of one member being pivoted to opposite sides of the band and to and within the corresponding ends of the arms of the companion member, the lower portions of the arms of the members being extended oppositely at angles to the upper portions, whereby the supports may be so turned 55 that the arms will be extended in parallelism with the barrel and the webs will be edge to edge at the end of the barrel.

4. A support for a flash-light having a 60 barrel, including a band adapted to be placed on the barrel, and a pair of substantially U-shaped supporting members each comprising two arms pivoted on the band, the lower end portions of each arm being 65 extended laterally toward and overlapped

by the corresponding portion of the other arm, said portions being slidably interconnected whereby the lower ends of the arms may be adjusted toward and from each other.

5. A support for a flash-light having a barrel, including a band adapted to be placed on the barrel, and a pair of substantially U-shaped supporting members, each comprising two arms pivoted on opposite sides 70 of the band, and an extensible and retractable web interconnecting the lower ends of the arms.

6. A support for a flash-light having a barrel, including a band adapted to be 80 placed on the barrel, and a pair of substantially U-shaped supporting members, each including a pair of arms and a web interconnecting the lower ends of the arms, the upper ends of the arms of one member being pivoted to and between the band and the corresponding ends of the arms of the other member, whereby the arms may be turned to a position in parallelism with the barrel, the arms being concavo-convex in 85 transverse section adapting those of the inner member to embrace the sides of the barrel when turned to said position, and those of the outer member to embrace those of the inner member.

7. A support for a flash-light having a barrel, including a band adapted to be placed on the barrel, and a pair of substantially U-shaped supporting members, each including a pair of arms, and lateral strips on the 100 lower ends of the arms, extended toward and overlapping each other, said strips being slidably interconnected whereby the lower ends of the arms may be adjusted toward and from each other, the upper ends 105 of the arms of one member being pivoted to and between the band and the corresponding ends of the arms of the other member, the lower end portions of the arms of the members, being extended oppositely 110 at angles to the upper portions, whereby the members may be so turned that the arms will be in parallelism with each other and the barrel, and the said strips will be edge to edge across the end of the barrel.

8. A support for a flash-light having a barrel, including a band adapted to be placed on the barrel, and a pair of substantially U-shaped supporting members, each including a pair of arms, and lateral strips on the 120 lower ends of the arms, extended toward and overlapping each other, said strips being slidably interconnected whereby the lower ends of the arms may be adjusted toward and from each other, the upper ends of the 125 arms of one member being pivoted to and between the band and the corresponding ends of the arms of the other member, the lower end portions of the arms of the members, being extended oppositely at angles to 130

the upper portions, whereby the members may be so turned that the arms will be in parallelism with each other and the barrel, and the said strips will be edge to edge

5 across the end of the barrel and the arms being concavo-convex in transverse section, whereby the arms of the inner member will

embrace the sides of the barrel when turned to said position, and the arms of the outer member will embrace those of the inner 10 member.

In testimony whereof, I have hereunto set my hand this 2nd day of March, 1918.

RICHARD NASON FRIEND.
